UNITED STATES PATENT OFFICE.

SAMUEL J. FUHRMAN, OF SCRANTON, PENNSYLVANIA.

COLLAPSIBLE BUCKET.

1,039,044.

Specification of Letters Patent. Patented Sept. 17, 1912.

Application filed December 21, 1911. Serial No. 667,184.

To all whom it may concern:

Be it known that I, SAMUEL J. FUHRMAN, a citizen of the United States, residing at Scranton, in the county of Lackawanna and State of Pennsylvania, have invented certain new and useful Improvements in Collapsible Buckets; and I do hereby declare the following to be a full, clear, and exact description of the invention, such as will enable others skilled in the art to which it appertains to make and use the same.

This invention relates to collapsible buckets and has for an object to provide a bucket constructed of water-proof or impervious fabric so built that it will collapse to practically a condition of one sheet of fabric superimposed upon another.

A further object of the invention is to provide a collapsible bucket having means at one side to serve as a spout for directing the contents of the bucket into a small receptacle when being poured out.

A further object of the invention is to provide improved structural features of converting a sheet of impervious fabric into a bucket.

With these and other objects in view the invention comprises certain novel constructions, combinations and arrangement of parts as will be hereinafter more fully described and claimed.

In the drawings:—Figure 1 is a perspective view of the improved bucket. Fig. 2 is a transverse sectional view through the tip of the bucket taken on line 2—2 of Fig. 1 and enlarged.

Like characters of reference indicate corresponding parts throughout the several views.

The improved bucket which forms the subject matter of this application comprises a single flexible sheet of water-proof or impervious material, indicated at 10, such sheet being cut V-shaped and with the sides brought over to substantially register but with one edge as 11 extending far enough

to overlap the other edge and form a seam as indicated at 12. To close the lower or apex end of the cone thus formed the extremity is brought upwardly as indicated 50 at 13 and secured under the edge 11 as indicated at 14 in Fig. 2, and the whole secured by a row of stitching 15 which completes the connection of the edges. For convenience in handling, a strap 16 is secured 55 thereon at its opposite ends as by the stitching 17. It will be noted that by reason of the form of the seam 12 the side of the bucket adjacent such seam is formed into a V-shaped opening which serves as a spout 60 when pouring the contents from the bucket.

The bucket described as above is particularly useful for automobilists who can carry such a bucket under the cushion of the seat and have it always convenient for filling radiators, or for use by hunters, campers or the like who can employ such bucket for a game bag or for any purpose or fold it up to be inserted in the pocket but have when required a bucket convenient for use 70 and reliable in the manner of holding liquids.

I claim:—

In a folding paper bucket rolled in the form of a cone and having an apex at its 75 lower end, a single V-shaped strip of paper, having two straight edges; one of the edges being turned over the other and contacting both sides of the latter for the greater part of its length, said apex being turned up and 80 received under part of the turned over edge, a line of stitching securing the turned over edge and the apex to the second mentioned edge, and a handle secured to both sides of the bucket. 85

In testimony whereof I affix my signature in presence of two witnesses.

SAMUEL J. FUHRMAN.
